MERCHANDISE DISPLAY STAND

William S. Leath, Birmingham, Ala., assignor to Ebsco Industries, Inc.

Original design application Feb. 24, 1969, Ser. No.
15,865. Divided and this application Oct. 17, 1969,
Ser. No. 19,840

Term of patent 7 years

Int. Cl. D6—01

U.S. Cl. D80—9

FIG 1

Fig 2

Fig. 3

Fig. 4

FIG. 1 is a perspective view of a merchandise display stand showing my new design.

FIG. 2 is a front elevational view thereof, the rear being identical to the front shown;

FIG. 3 is an elevational view showing one side thereof, the side not shown being identical to the side shown; and,

FIG. 4 is a top plan view thereof.

This is a division of design application Ser. No. 15,865, filed Feb. 24, 1969.

I claim:

The ornamental design for a merchandise display stand, as shown and described.
